UNITED STATES PATENT OFFICE.

WILLIAM O. JOHNSON, OF BLUNT, SOUTH DAKOTA.

ACCOUNT-BOOK.

1,113,159.

Specification of Letters Patent.

Patented Oct. 6, 1914.

Application filed July 19, 1909. Serial No. 508,525.

To all whom it may concern:

Be it known that I, WILLIAM O. JOHNSON, of Blunt, in the State of South Dakota, have invented new and useful Improvements in Account-Books, of which the following is a specification.

My invention relates to book-keeping and its objects are first, to provide forms of ruling for the pages of the book whereby the 10 person using the same may rapidly post items in their proper places and quickly ascertain the condition of any account without referring to the headings of the different columns in the account; second, to provide 15 an index whereby the book of which it forms a part may be quickly opened at any desired page or account without thumbing the leaves or taking notice of the numbers on the pages or headings of the accounts; third, 20 to provide a means whereby the new balances of accounts, which have changed since the time of taking the preceding proof, may be proven without the necessity of referring to or transcribing in any manner the balances 25 of accounts that have not changed; fourth, to provide a means whereby the sum of all debit balances and the sum of all credit balances contained in the ledger may be quickly computed without referring to 30 or transcribing in any manner the balances of accounts that have not changed. The foregoing objects are accomplished without opening the ledger at any time during the process at accounts the balances of which 35 remain unchanged.

A practical embodiment of the invention is represented in the accompanying drawings, forming a part of this specification, in which the same characters of reference indicate corresponding parts in all of the 40 views.

Figures 1 and 3 represent a face view of an account book showing index sheet B and supplementary proof sheets D and E. The 45 proof sheets are attached to the inside of the back cover of the ledger at the point A, common to both Figs. 1 and 3. Fig. 4 shows an end view of Fig. 3. The right hand end of Fig. 2 shows the appearance of an end 50 view of Fig. 1, and the left hand end of Fig. 2 shows the appearance of an end view of Fig. 11. Figs. 5, 8, 9 and 10 show modifications of the form of proof sheet shown in Fig. 3. Figs. 6 and 7 illustrate one method of detachably attaching 55

the proof sheets to the back cover of the ledger. Fig. 11 shows the appearance of the back of the index sheet seen in Fig. 1 and also a modification of the form of ruling on page 195 of Fig. 1.

The form of ruling shown on page 195 of Fig. 1 consists of vertical columns on the right hand portion for credit balances and credits and columns on the left hand portion for debit balances and debits. The vertical rulings in the middle may be shaded and thus aid the eye in distinguishing between the debit and credit sides. The date column is placed between the two sides of the account so as to be convenient for use 60 with either side. Where desired it may be placed along the left hand margin of the space devoted to each account. In posting, the date column is the first column sought after having opened the ledger at the desired account. By placing it in the middle of the space devoted to each account and shading the vertical rulings on either side it can be readily distinguished. Credit items are invariably posted on the right and debit 65 items on the left hand side, thereby eliminating the liability of posting debit items in the credit column and vice versa, a frequent occurrence with the forms in common use.

Page 194 of Fig. 11 shows a modification 70 of the form on page 195 of Fig. 1. This modification is adapted for use in banking institutions where debit balances or overdrafts are rare and are commonly entered in the balance column in red ink thereby distinguishing them from the credit balances. On page 194 of Fig. 11 the debit balance or overdraft is distinguished by small 75 vertical figures. By this modification the debit balance column is combined with the credit balance column and room made for extra debit columns or checks in detail. The checks are generally more numerous than the deposits or credits. Either of the forms shown on pages 194 or 195 may be used as 80 the form of ruling on the cards of so-called "card ledgers."

The index sheet B, Fig. 1, is preferably made of press board or other stiff material covered with paper and having a flexible 85 portion F, Fig. 2. It is made a few inches wider than the pages of the ledger so that when bound with the leaves the ruled portion will project beyond the side edges of the leaves. The projecting portion of each 90

110

index sheet is ruled with horizontal spaces for each account in the section of the ledger adjacent to the corresponding side and with vertical columns for the name and number of each account indexed and having a vertical check column in which a check mark may be entered when an item is posted to the corresponding account.

The check column may be covered with 10 silicious or other material permitting erasures of the check marks after each proof. The accounts should be arranged alphabetically in the ledger and will appear in the same successive order on the adjacent index 15 sheet. In the upper corner near the outer margin are placed the inclusive initials of the accounts indexed on the same side of the sheet.

The edges of the leaves of the book have 20 extensions X about half an inch wide and the extension on each leaf extends upward to a point opposite the line on the index sheet intended for indexing the last account on the first page of the leaf. The exposed 25 part of each extension X may be covered with an extra covering of paper if desired. Instead of the extensions of the leaves, so-called "index tabs" may be used; the tab on each leaf being arranged opposite the horizontal spaces on the index sheet in which 30 are indexed the accounts that appear on the first two pages following the tab. The index C is a duplicate of B and is arranged on the back of the preceding sheet, thus 35 forming a double index.

The index sheets are arranged at successive intervals in the book as shown in Fig. 2; the number of pages or accounts between each index sheet depending on the number 40 of accounts that may be indexed on the face of each sheet. For simplicity of illustration only two of the thirty accounts on pages 181 to 210 are noted on the index in Fig. 1. The account on page 204 would be indexed 45 on line 204 of the index. The book would be opened at this page or account by grasping the tab or extension of the leaf opposite the corresponding name and number on the index and turning at once all of the unturned leaves that precede this account.

The index may be used as a general index with any kind of book and the name column may be used for entering any desired designations. The index sheets may be detachably bound together with the leaves of the book by means of any so-called "loose leaf" binder.

Two pages of proof sheets are shown in Fig. 3. Each page has vertical columns on 60 one portion for entering the old debit balances of changed accounts, the debits and the new credit balances of changed accounts; and vertical columns on the other portion for entering the old credit balances of 65 changed accounts, the credits and the new

debit balances of changed accounts. The footings of these columns are denoted by the letters *a*, *b*, *c*, and *d*, *e*, *f*, respectively.

Between the two sides of each proof sheet is a vertical number column in which the 70 numbers of the successive accounts may be printed permanently or written at the time the memoranda of the account are transferred to the proof sheet. The main portion of each sheet is divided horizontally 75 into spaces for each account in the corresponding section of the ledger and with a horizontal space at the top for forwarding the footings of the preceding sheet. The horizontal space devoted to each account is 80 arranged opposite the horizontal space on the index sheet devoted to the corresponding account. At the top of each proof sheet is a space for entering the date and below the space for the footings of the columns 85 are spaces for adding the sums of the columns on each side to prove the new balances, and also spaces for computing the total credit balances and the total debit balances. The sum of *a*, *b*, and *c* on each sheet is denoted by *P* and the sum of *d*, *e*, and *f* is denoted by *P'*. The equality of the sums denoted by *P* and *P'* is proof that all of the new balances are correct. An equivalent 90 way of proving the new balances is to subtract any part of the items designed to be entered on one side from the items on the other side. The total credit balances or the sum of all the credit balances contained in the ledger, including both the changed and 95 the unchanged accounts, is computed by 100 adding to the total credit balances from last proof, or the sum of all the credit balances contained in the ledger at the time of and determined by the preceding proof, the sum 105 of the new credit balances of changed accounts, *c*, and subtracting from the sum of these the sum of the old credit balances of changed accounts, *d*. The total debit balances or the sum of all the debit balances 110 contained in the ledger is computed in the same manner. It is obvious that where the sums of the debits and credits are equal their sums need not be taken into consideration in proving the new balances; but where their 115 sums are unequal and where such sums for that portion of the ledger which it is desired to prove can not be obtained from auxiliary books their sums must be computed as shown by *b* and *e* on the first proof sheet, 120 page 7, in Fig. 3.

The supplementary proof sheets shown in Fig. 3 are preferably made of press board covered with paper and may be coated with silicious material permitting erasures. 125 They may be made with one page for each section or index sheet in the ledger as shown in Figs. 2 and 4. If not designed to be coated with silicious material they should be made with a greater number of pages. 130

The first page or cover is attached to the inside of the back cover, I, of the ledger, Figs. 2 and 4, by means of the flexible strip A, Fig. 2 and 4, so that when the sheet E is closed the back or bound edge G Fig. 4, may be folded over on said flexible strip A inside of the back cover I, of the ledger into the space H, Fig. 2.

Fig. 5 is a modified form of the proof sheets shown in Fig. 3. In this form the memoranda of the changed accounts may be entered on successive lines instead of being entered on the horizontal line opposite the corresponding line of the index sheet. Fig. 15 5 represents a book of 320 pages in which the left hand pages are numbered consecutively from 1 to 160 and having the right hand pages inverted and numbered consecutively from 161 to 320 beginning with the 20 page adjacent to the back cover of the book. The left hand page when in use will lie contiguous to the index sheets of the ledger and by inverting the book the right hand pages from 161 to 320 when in use will also be 25 contiguous to the ledger, thus making it more convenient to transfer memoranda from the accounts in the ledger to the proof sheets. The proof sheets when bound in this form need not be attached to the ledger. 30 They may however be attached by means of the detachable mechanism shown in Fig. 6, in which I represents the inside of the lower corner of the back cover of the ledger with the stationary button L attached thereto. 35 J represents the outside of the lower front corner of the book of proof sheets shown in Fig. 5, with the eyelet or opening K inserted therein. When attached the eyelet K will be clasped over the button L. A like button and eyelet will fasten the upper corner of the book of proof sheets to the inside of 40 the back cover of the ledger at the top. Like eyelets are inserted in the outside of the back cover of Fig. 5 near the side 45 edge so that the back cover thereof may be attached to the ledger when using the inverted pages 161 to 320. One book of proof sheets may be used with a series of any number of ledgers.

50 Fig. 7 shows a sectional view of Fig. 6 with the cover, J, of the book of proof sheets attached to the back cover, I, of the ledger. This fastening device is not claimed as new. Any other convenient fastening device may be used.

Figs. 8 and 9 are modifications of the forms shown in Figs. 3 and 5 and may be employed in any business although designed for use in banking. The debit balances are 60 to be entered in red or differently colored ink, thereby distinguishing them from the credit balances. In Figs. 8 and 9 the debit balances or overdrafts are distinguished by small vertical figures. Fig. 9 is designed 65 for use where the sum of the checks or deb-

its and the sum of the deposits or credits may be obtained from auxiliary books and need not be recomputed on the proof sheet.

In each of Figs. 5, 8 and 9 the new balances are proven and the total credit balances and the total debit balances contained in the ledger are computed in the same manner as described in connection with Fig. 3.

Fig. 10 illustrates another modification having vertical columns for debit balances, 75 credit balances and the numbers of the accounts with a horizontal space at the top for the date and another at the bottom for footing the columns. The main portion is divided horizontally into spaces for the different accounts with a space above these for forwarding the footings of the preceding sheet. The space for each account is arranged so that when the book is attached to the ledger the space for each account will be opposite the space devoted to the same account on the complementary index sheet.

Either of the forms shown in Figs. 3, 5, 8, 9 or 10 may be covered with silicious or other material permitting erasures. Either of the forms may be ruled on ordinary paper and bound in book form as shown in Fig. 5 either with or without the right hand pages inverted. Either of the forms 95 may be attached to the ledger permanently or with the detachable device shown in Figs. 6 and 7 or with any other mode of attachment.

In posting with the methods in common use it is necessary to refer to an index to ascertain the number of the page in the ledger on which an account appears and then thumb the pages of the ledger back and forth until the required account is 100 found; after which the headings of the columns must be consulted to find the proper column in which to post the item. In computing the new balances it is again necessary to consult the headings of the columns of the account. In proving the new balances and computing the total credit balances and the total debit balances every account must be examined and every balance in the ledger entered on a proof sheet 105 or balance book and every balance added to obtain the totals. In posting with the improved account book described herein the book may be opened almost instantly at any desired account and the item posted in 110 the proper column without consulting the headings of the columns. In computing the new balances the sum of the entries since the last balance on the same side that such balance appears are invariably added to 115 such balance and the sum of the entries on the opposite side for the same period are subtracted from these, thus greatly eliminating the liability of error in computing the new balances. In computing and prov-

120
125
130

ing the new balances and computing the total credit balances and the total debit balances the bookkeeper is enabled by reference to the check marks on the index sheets to turn to each successive account where an entry has been made since taking the last proof and transfer the necessary memoranda thereof to the proof sheet without opening the ledger at accounts the balances of which remain unchanged.

In each of Figs. 5, 8 and 9 is shown all the actual work required in proving the new balances and computing the sum of all the credit balances and the sum of all the debit balances in a ledger having 240 accounts where changes have taken place in five per cent. of the number of accounts since the time of taking the last proof. The 228 unchanged accounts, ninety-five per cent. of the whole number, are completely eliminated in the computation; thereby saving much time and labor, an important item of expense. By the use of this improved method business houses or banking institutions may prove their books and obtain a statement of their condition daily or weekly with comparatively little labor.

What I claim as my invention and desire to secure by Letters Patent is—

30 1. An account book having the pages thereof separated into groups, index sheets positioned between the various groups and projecting beyond the edges of the leaves thereof, both sides of each index projecting 35 portion having numbered horizontal lines and adjacent faces of each pair of adjoining index sheets being similarly ruled and lettered to serve as a summary of the inclosed group, one face of each index sheet 40 being designed to expedite reference to any

leaf of the account book in the following group and the opposite face being designed to assist in the transmitting of notes from the leaves of the preceding group to a supplementary proof sheet adapted for use in 45 conjunction with said account book.

2. The combination with an account book having the pages thereof separated into groups, of index sheets positioned between each two adjoining groups and projecting 50 outwardly beyond the edges of the leaves thereof, both faces of each index sheet having numbered horizontal lines and adjacent faces of each pair of adjoining index sheets being similarly ruled and lettered to serve 55 as a summary of the inclosed group, projections arranged on each leaf of the book opposite the space between two adjoining numbered lines of said index sheets, a supplementary proof sheet, means for flexibly 60 attaching said proof sheet to said account book, an appropriate space being provided in the latter to receive said proof sheet, means for foldably disposing said proof sheet in the space, the whole being arranged 65 so that one face of each of said index sheets may be used for reference to the following group of said account book and the opposite face of said index sheet be used for the transmission of accounts from the pages of 70 the preceding group to said supplemental proof sheet.

In testimony whereof I have signed my name to this specification in the presence of two subscribing witnesses.

WILLIAM O. JOHNSON.
